UNITED STATES PATENT OFFICE

151,217

DESIGN FOR A COMBINED ASHTRAY, GLASS,
AND POKER CHIP HOLDER

Mary Buehren, Winnetka, Ill.

Application December 3, 1946, Serial No. 135,236

Term of patent 14 years

(Cl. D85—2)

To all whom it may concern:

Be it known that I, Mary Buehren, a citizen of the United States, residing at 1422 Edgewood Lane, Winnetka, Cook County, Illinois, have invented a new, original, and ornamental Design for a Combined Ash Tray, Glass, and Poker Chip Holder, of which the following is a specification, reference being had to the accompanying drawing, forming a part thereof, in which

I claim:

The ornamental design for a combined ash tray, glass, and poker chip holder, as shown.

MARY BUEHREN.
